UNITED STATES PATENT OFFICE.

WALTER C. WOOD, OF CRANSTON, RHODE ISLAND.

BRACELET AND THE LIKE.

1,394,877.

Specification of Letters Patent. Patented Oct. 25, 1921.

Application filed January 15, 1921. Serial No. 437,546.

To all whom it may concern:

Be it known that I, WALTER C. Wood, a citizen of the United States, residing at Edgewood, city of Cranston, in the county 5 of Providence and State of Rhode Island, have invented certain new and useful Improvements in Bracelets and the like, of which the following is a specification.

This invention relates primarily to an improved construction of chain more particularly adapted for use in the jewelry art in the construction of bracelets, necklaces, and the like.

The object of this invention is to provide 15 a novel construction of chain in which links are hinged or yieldably connected together.

A further object of the invention is to provide a chain of this character which is simple and inexpensive in construction and 20 which is composed of a series of links, each having an integral portion adapted to be locked into an integral portion of the next adjacent link whereby the links are connected together and the chain is rendered 25 very flexible.

With these and other objects in view, the invention consists of certain novel features of construction, as will be more fully described, and particularly pointed out in the 30 appended claims.

In the accompanying drawings:

Figure 1 is an edge view of my improved chain as made up into a bracelet form, a portion only of the bracelet links being 35 shown, the balance being indicated in dotted lines.

Fig. 2 is an enlarged view of one of the links as cut from sheet stock.

Fig. 3 is a side elevation partly in section, 40 illustrating the blank shown in Fig. 2, as dapped or swaged forming the body portion into concave shape and bending the integral extending members into shape to be connected to those of the next adjacent link.

Fig. 4 is an enlarged end view of the 45 T-shaped hinged member with its trunnions raised above the plane of the tongue.

Fig. 5 is a view illustrating two of the link members as hingedly connected together 50 with the gems shown in dotted lines.

Fig. 6 is a sectional elevation showing a pearl or gem as set in the concaved body portion of the link and riveted therein by a pin which extends outward from the body 55 of the gem.

Fig. 7 is a modification illustrating one of

the hinge members as made in bail form and the other in the form of a bendable tongue.

With reference to the drawings, 10 designates the body of the link which may be 60 constructed from sheet stock, first into the form illustrated in Fig. 2, in which a pair of parallel, laterally-extending bendable fingers 11 project from one edge thereof and a single tongue 12 extends from the opposite 65 end thereof, which tongue is provided with laterally-extending hinge trunnions 13. The next operation is to swage this body portion into the form illustrated in Fig. 3, the body of which is formed substantially concave- 70 convex providing a shallow setting for the reception of a gem 14 which, in this particular case, is an artificial pearl.

These hinged trunnions 13 are shown as being raised above the plane of the outer 75 surface 15 of this tongue member and this tongue is turned inwardly so that its extremity is about parallel with the inner or contacting surface 16 of the body of the link so that when the hinged fingers 11 are folded 80 about these trunnions the outer edge 17 of the finger will be substantially parallel with the outer face 18 of the body of the link and the inner portion 19 at the bend will be in substantial alinement with the 85 inner surface 16 of the body of the link so that when placed upon the arm of the wearer no part of the hinged portion will extend beyond the engaging inner surfaces of the links to abrade or irritate the flesh; 90 also by this arrangement of hinge the same is carried inward as far as possible so as to render the joint inconspicuous through the openings between the gems of the bracelet, but the most essential reason for offsetting 95 these hinge portions inwardly from the outer edge of the body portion, is so as not to interfere with the gems when the bracelet is set in a straight line in which position the peripheries of the gems should practically 100 contact with each other.

In forming a gem such as an artificial pearl, or the like, the glass body portion of the pearl is usually formed upon the stem 20 leaving a portion projecting therefrom, 105 which portion is adapted to extend through the opening 21 in the bottom of the body portion and is headed over as at 22 against the inner surface of the link thus permanently securing a gem in each link.

In order to connect the ends of the bracelet together an ordinary snap construction

as at 23, is provided on the ends of the abutting links whereby the ends of the bracelet may be readily connected about the arm of the wearer and disconnected to be removed therefrom when desired.

I do not wish to be restricted to the exact construction of hinged members above described as in some cases a bendable tongue 24 may be formed on one edge of the link 10 and a loop or bail 25 on the other end of each link, and the different links joined together by passing the tongue of one link through the bail or eye of the next adjacent link, or any other suitable means of hingedly 15 connecting the different links together, may be employed.

My improved bracelet chain is very simple and practical in construction, is strong and durable and the parts may be readily connected together for the support of gems 20 and when so constructed each link forms a setting which is quite inconspicuous being practically covered by the pearls mounted therein.

25 The foregoing description is directed solely toward the construction illustrated, but I desire it to be understood that I reserve the privilege of resorting to all the mechanical changes to which the device is

susceptible, the invention being defined and 30 limited only by the terms of the appended claims.

I claim:

1. An article of the character described comprising a plurality of links, each having 35 a shallow concaved body constructed of a sheet metal plate with oppositely projecting extensions integral with the outer edge of said body both of said extensions being offset inwardly and one of the extensions being 40 folded to loosely engage the opposite extension of the next adjacent link to hingedly connect the links together.

2. A chain bracelet comprising a plurality of sheet metal links, each having a shallow 45 concaved gem-receiving body portion with a T-shaped tongue extending from one side and bendable fingers extending from the opposite side thereof, the fingers of one link being folded about the cross bar of the next 50 link to hinge them together both hinge members being set to extend inwardly from the outer edge of the body to position the pivotal axis of the hinge on a plane substantially midway between the inner and outer 55 surfaces of the link body.

In testimony whereof I affix my signature.
WALTER C. WOOD.
